Samuel G. Thomas Inventor

UNITED STATES PATENT OFFICE.

SAMUEL THOMAS, OF BURNETT, WISCONSIN.

IMPROVEMENT IN HARVESTING-MACHINES.

Specification forming part of Letters Patent No. **23,961**, dated May 10, 1859.

To all whom it may concern:

Be it known that I, SAMUEL THOMAS, of the town of Burnett, in the county of Dodge, in the State of Wisconsin, have invented a new and useful Improvement on the Harvester, (either reaper or mower;) and I do hereby declare that the following is a full, clear, and exact description of the construction and operation of the same, reference being had to the annexed drawing, making a part of this specification.

Figure 1 is a perspective view.

K L is the pole and attachment to the harvester F G; A B, a false pole, (my invention,) attached at A to the main pole K L. E C is a metallic gage connected with the false pole

at E by bolt and with main pole at D by bolt or equivalent. The gage may be moved in the direction of E C and C E, thereby varying the draft or side pressure of the pole as may be required. E M is whiffletree, fastened to false pole at B.

What I claim as my invention is—

The false pole K B, with its attached sliding gage E C, which may be adjusted at pleasure, so as to prevent side draft and pressure upon the near horse, in the manner and for the purpose specified.

SAMUEL THOMAS.
